APPARATUS FOR CLEANING REVOLVING-FLAT CARDING MACHINES.

Application filed May 10, 1924, Serial No. 712,373, and in France May 24, 1923.

This invention relates to revolving-flat carding engines for carding vegetable fibre such as cotton, and more particularly it relates to improved means for obtaining a very much cleaner and, therefore, an improved and better product than heretofore.

As is well known to those skilled in the art, vegetable fibre as it is fed to the card contains much dirt and other impurities which, notwithstanding the functions of the lickerin and mote knife to clean the fibre, are carried during the operation of the card on to the surface of the main cylinder. After a time so much of this dirt becomes lodged deep in the cylinder clothing where it cannot be removed by the revolving-flat, that the carding engine must be stopped to remove the impurities, or for "stripping" as it is called by the trade. In the meantime, however, owing to the varying degree of cleanliness of the fibre on the main cylinder during the working period, varying quantities of the impurities are transferred by the doffer to the product with the result that the product is not uniform. In practice it has been found necessary to strip revolving flat top carding engines, that have no mechanical means for doing away with the impurities, by hand or otherwise about every two to four hours. The highest degree of purity of the product is attained just after the cylinder and doffer have been stripped and its purity decreases considerably toward the end of the working period. During the period required for stripping, the card is not producing which is a serious disadvantage.

Efforts have been made to obtain a constant degree of purity of the product by the provision of mechanical devices which it was hoped would automatically clean the main cylinder while operating and thus prevent loss of production by forced stoppage for stripping. These have taken the form of a clothed roller having a higher peripheral speed than the cylinder, which consequently acts as a brush. Such a device has been tried, without appreciable benefit, either between the rear end of the revolving-flat and the doffer or below the main cylinder between the doffer and the lickerin. When the so-called "cleaning roller" is located in the first-named position, i. e. in front of the doffer, the impurities lodged in

the cylinder clothing as hereinbefore described are loosened to such an extent that much of this impure material is carried into the carded product by the doffer. When this roller is located in the second-named position, i. e. behind the doffer, then it still permits the transfer of impurities from the main cylinder to the product and functions to clean from the cylinder clothing merely what impurities may be left therein after the doffer has done its work. Accordingly, the provision of such a cleaning roller as just described does not avoid the eventual necessity of periodical shut-downs of the card for stripping the main cylinder and doffer of the impurities that have lodged in the clothing thereof.

The object of the present invention is to provide a mechanical cleaning device that will maintain the impure cotton fibre, as it is delivered to the main cylinder by the lickerin, in such an incompact condition and in such a position on the wires of the main cylinder clothing that the revolving-flat may properly and efficiently perform its function of removing the impurities and thus cause the carding engine continuously to deliver a uniform product having the highest degree of purity.

In order to attain this object it has been found essential to locate the mechanical cleaning device at a point with relation to the main cylinder where the impure fibre delivered to the said cylinder can not eventually find its way to the doffer and thence to the product. Accordingly this invention contemplates a cleaning device located between the lickerin and the forward end of the revolving-flat since, when in this position with relation to the main cylinder the impurities if removed from the cylinder are thrown back by the device upon the outer-ends of the wires of the cylinder clothing where they can readily be seized and carried away by the flats. Due to the location of the cleaning device adjacent the forward end of the revolving flat, the working flats seize the impurities in the fibre directly after the fibre has been acted upon by the cleaning device and before there is an opportunity for the impurities to become lodged at the bases of the wires forming the cylinder clothing. The device functions as an agitator to main-

tain the fibre at the outer ends of the cylinder needles prior to its passage to the revolving-flat. Thus, the fibre that is carried beyond the revolving-flat for the doffing action of the doffer has had the dirt and impurities fully removed by the working flats and only clean and useful fibre goes into the product. Furthermore, a carding engine provided with our novel cleaning device may be run continuously without stopping production for stripping or for grinding, an advantage recognized by cotton textile manufacturers as of the greatest importance.

To the accomplishment of the foregoing object, the invention comprises the features and combinations of parts hereinafter described and then particularly pointed out in the appended claims.

The features and scope of the invention will best be understood from a description of the preferred embodiments thereof illustrated in the accompanying drawings, in which:

Figure 1 is a view, in longitudinal section, of a revolving-flat carding engine provided with our novel mechanical cleaning device;

Figs. 2 and 3 show a cross-section and elevation respectively of one form of the cleaning device;

Figs. 4 and 5 are like views of another form of the cleaning device;

Figs. 6 and 7 are like views of still another form the cleaning device may take;

Figs. 8 and 9 are like views illustrating a fourth form of the cleaning device;

Figs. 10 and 11 are like views showing a fifth form of the cleaning device; and

Fig. 12 is a view in detail of the construction of the teeth of the comb used on certain of the cleaning device types.

The preferred cleaning device comprises clothing, in the form of comb-teeth or needles, of the kind shown in Figs. 10 and 12, mounted on a rotatable member in separated groups as illustrated by Fig. 5. While this construction is preferred other effective cleaning devices may be produced by various combinations and arrangements within the skill of the artisan, the present invention not being so much concerned with this detail as with the broad principle of a mechanical cleaning device, for revolving-flat carding engines for carding cotton or like vegetable fibre, so located with relation to the main cylinder and the revolving-flat that dirt and other impurities are effectually separated from the good fibre and the main cylinder clothing is left with only pure fibre thereon when said fibre filled clothing reaches the doffer.

In the preferred embodiment of the invention illustrated in Figs. 1, 5, 10 and 12 of the drawings, A is the main cylinder of a revolving-flat carding engine, B is the

lickerin, G is the revolving-flat, and I is the doffer. All of these parts may be constructed in accordance with approved practice for carding cotton or like vegetable fibre, and combined therewith are the usual and necessary features of cotton cards, some of which are indicated in Fig. 1 as will be recognized by those who are familiar with cotton mill machinery.

As shown by Fig. 1, between thelickerin B and forward end of the revolving-flat G we have provided a cleaning device in the form of a shaft D provided with a support for an arrangement of wire teeth C, which in the preferred form are bent at a reverse angle to the angle of the wires forming the clothing of the main cylinder A (see Fig. 10) and are of such length, compared to the distance that the shaft D is spaced from the cylinder A, that they intermesh with the cylinder clothing (see Fig. 1) as the cleaning device and cylinder are revolved in opposite directions. Thus at the tangent zone the two surfaces are moving in the same direction. As indicated by the arrows on Fig. 1 the main cylinder rotates in a clockwise direction and the cleaning device rotates in a contra-clockwise direction. The working-flats travel over and along the upper portion of the main cylinder in the same direction as that of the circumferential face of the cylinder which they overlie, as is usual in engines for carding cotton and like vegetable fibre.

As illustrated by Figs. 2 to 11 the cleaning device may take several forms. In Figs. 2 to 5 inclusive the teeth C' are straight and project radially from a supporting bar C² on the shaft D, forming a comb. Fig. 5 differs from Fig. 3 only in that the teeth of the comb are not continuous, gaps E being provided at intervals along the shaft. C³ in these four figures represents a counterweight.

The construction of the cleaning device illustrated by Figs. 6 to 9 inclusive shows relatively short wire teeth F secured on the circumferential surface of a roll K, mounted on the shaft D, said roll having a correspondingly large diameter so that the ends of the wires will sweep through a circular path of the same diameter as that of the teeth C'. Fig. 9 differs from Fig. 7 in that the wires F' take the form of a series of tufts arranged in a spiral about the roll K.

The preferred form of wire teeth and their mounting on the shaft D is illustrated by Fig. 10 and in enlargement by Fig. 12. The teeth C (Fig. 12) are constituted by flat wires whose extremity is twisted 90° and bent at an oblique angle to the shank portion. The point may be hardened. The shanks of the teeth are held in a bar L' fastened just above the bent knee of a metal rail L secured lengthwise of the bar C² on the shaft D. The bent wires C bear normally

against the free edge of the rail L, the line of contact being just outward of the knees of the bent wires, but they can yield rearwardly as they engage and pass through the clothing of the main cylinder A. On springing back they are arrested by the rail L and thus vibration is prevented. The wire teeth C may form a continuous comb across the cleaning rollers, as illustrated by Fig. 11, but we prefer the discontinuous arrangement illustrated by Fig. 5.

In any of the illustrated forms the wire teeth of the cleaning device may be either straight or bent as in Fig. 10 and their points 15 may be radially directed or more or less inclined. The cross-section of the teeth may be round or flat, and they may have conical points.

While we have termed the device C—D a 20 "cleaning device" for want of a better descriptive term, it does not, by its own operation, actually clean the main cylinder clothing. Our cleaning device does not perform the function of a hand stripper because no 25 cotton is removed by it from the main cylinder clothing. What our cleaning device does is to take the cotton fibre, while in its impure condition as it lies in the clothing of the main cylinder just after delivery thereto by 30 the lickerin, and lift this cotton fibre up through the wires or needles of the cylinder clothing, between which it has become pinched, so that it will lie at the outer surface of the cylinder clothing when brought by the 35 rotation of the cylinder within the range of operation of the working flats. In operating a cotton carding engine that does not have our cleaning device there is probably three times as much cotton on the clothing 40 of the main cylinder, as it travels beneath the working flats, as there is when our cleaning device is used. This means that the cotton becomes packed in the cylinder clothing, the pure fibre with the impure fibre, in a 45 mixture from the impurities cannot be segregated by the revolving-flat. Consequently much impure fibre passes to the product through the operation of the doffer. A cotton card having our cleaning device combined with the lickerin and revolving-flat, 50 as hereinbefore described, functions to maintain the cotton in an incompact condition at the outer surface of the cylinder clothing while it approaches the forward end of the 55 revolving-flat and enables the working flats thereof to efficiently perform their function of removing the impurities.

The invention may be applied to compound carding engines with both revolving-flat and roller cards, the cleaning device being arranged as heretofore described between the lickerin and the forward end of the revolving-flat.

The nature and scope of the present invention having been indicated and its preferred

embodiment having been specifically described, what we claim as new, is:—

1. In combination with a carding engine for cotton and like vegetable fibre of the type having a lickerin, main cylinder, revolving-flat, and doffer, a rotary cleaning device having teeth each bent to form a knee and being mounted for engagement with the cylinder clothing so that while engaging therewith the knees point in the same 75 direction as those of the teeth forming the cylinder clothing, and means for supporting said device for working on said main cylinder between the lickerin and the forward end of the revolving-flat, said device and cylinder being rotated in opposite directions. 80

2. In combination with a carding engine for cotton and like vegetable fibre of the type having a lickerin, main cylinder, revolving-flat, and doffer, a rotary cleaning device having comb-like teeth working on the main cylinder and disposed between the lickerin and the forward end of the revolving-flat, and means carried by said device for damping vibration of the free ends of 90 said teeth. 85

3. In combination with a carding engine for cotton and like vegetable fibre of the type having a lickerin, main cylinder, revolving-flat, and doffer, a rotary cleaning device working on the main cylinder and disposed between the lickerin and the forward end of the revolving-flat having teeth that interengage with the teeth of the cylinder 95 clothing. 100

4. In combination with a carding engine for cotton and like vegetable fibre of the type having a lickerin, main cylinder, revolving-flat, and doffer, a cleaning device disposed between the lickerin and the forward end of the revolving-flat adapted to work upon the fibre on the cylinder clothing and maintain it at the outer surface thereof for seizure by the working flats. 105

5. In an engine for carding cotton and like vegetable fibre, a rotary cleaning device for working on the main cylinder, having long, flat, resilient tongue-like teeth, the outer ends of which are rectangularly 110 twisted with respect to their shanks. 115

6. In an engine for carding cotton and like vegetable fibre, a rotary cleaning device for working on the main cylinder comprising a shaft, a support on the shaft, a rail secured lengthwise of the support, and bent teeth secured to said rail and engaging the edge of the rail along a line just outward of the bends in said teeth. 120

7. A carding engine for cotton and like vegetable fibre comprising a main cylinder and the following devices cooperating with said cylinder and arranged about said cylinder in the sequence named, first a lickerin, then a rotary cleaning device, and then a revolving flat. 125 130

8. The method of producing a substantially pure product from carded cotton or like vegetable fibre which consists in feeding the impure cotton to the clothing of the main cylinder of a revolving-flat cotton carding engine, maintaining said cotton while still charged with impurities at the outer surface of said cylinder clothing until

carried to the working flats, removing the impurities by operation of the revolving flat, and finally doffing the cleaned cotton which remains on the cylinder clothing after passing the revolving flat. ¹⁰
